UNITED STATES PATENT OFFICE.

CURTIS HUSSEY VEEDER, OF HARTFORD, CONNECTICUT.

DESIGN FOR A CASE FOR REGISTERS.

SPECIFICATION forming part of Design No. 29,179, dated August 9, 1898.

Application filed July 5, 1898. Serial No. 685,183. Term of patent 14 years.

To all whom it may concern:

Be it known that I, CURTIS HUSSEY VEEDER, a citizen of the United States, residing in the city of Hartford, county of Hartford, State 5 of Connecticut, have invented a certain new and original Design for Cases for Registers, of which the following is a specification, reference being had to the accompanying drawings, forming a part hereof.

My invention relates to designs for cases or shells for registers, such as cyclometers and other like instruments; and it consists in a case having the shape and configuration substantially as shown in the accompanying 5 drawings, in which—

Figures 1, 2, and 3 are respectively a plan view, a side elevation, and an end elevation of a case or shell which embodies my design.

Referring to the drawings, it will be seen 10 that in accordance with my design the case

or shell, when seen in side elevation, presents the appearance of two polygonal bodies *a a*, merged into one along one of the flat sides of each. In parallel faces *b b* of the two bodies *a a* are transverse parallel openings *c c*. 25

The leading feature of my design is the body having the appearance of two polygonal bodies merged into one along one of the flat faces of each.

What I claim, and desire to secure by Letters Patent, is—

The design for a case for registers, substantially as shown and described.

This specification signed and witnessed this 24th day of June, A. D. 1898.

CURTIS HUSSEY VEEDER.

In presence of—

D. J. POST,
E. B. SMITH.
